UNITED STATES PATENT OFFICE

HENRY KOLAR, OF EXETER, NEBRASKA

AGITATOR FOR WASHING MACHINES

Application filed December 12, 1929. Serial No. 413,514.

The present invention relates to certain new and useful improvements in agitators such for example as used in connection with a washing machine, and the primary object of this invention is to provide a double agitator for this purpose.

A still further object of the invention is to provide an agitator embodying a disk-like body formed on the lowermost end of a shaft adapted to be coupled to the driving shaft of the washing machine, and further wherein the disk-like body has formed integrally therewith upon the upper face thereof a plurality of ribs or vanes extending radially from the lowermost end of said shaft in conjunction with a second agitator keyed on the upper end of said shaft and embodying a disk-like body having a plurality of circumferentially spaced legs depending downwardly and outwardly therefrom at the periphery thereof.

A still further object of the invention is to provide an agitator for use in wash tubs including a lower agitator and an upper agitator whereby to thoroughly shift and agitate the articles in the tub adjacent the bottom and top of the tub.

Other objects and advantages of the invention will become apparent during a study of the following description, taken in connection with the accompanying drawings wherein:

Figure 1 is an elevational view of the upper agitating member,

Figure 2 is a top plan view thereof,

Figure 3 is a view partly in section and partly in elevation of the lower agitator,

Figure 4 is a top plan view thereof,

Figure 5 is a bottom plan view thereof,

Referring to the drawings, it will be seen that my improved agitator comprises a lower agitating member and an upper agitating member embodying a shaft 5 which may be of hollow construction, said shaft 5 at its lower end having formed integrally therewith a disk-like body 6. The disk-like body 6 has formed integrally therewith and rising therefrom radial vanes or wings 7, the wings 7 radiating from the lower end portion of said shaft 5.

The shaft 5 at its upper end is formed or provided with a plurality of relatively short

longitudinal grooves 8 to adapt it for keyed connection with the corresponding part of the drive shaft, not shown, of the washing machine.

Formed exteriorly on the shaft 5 and extending longitudinally thereof are ribs 9 for a purpose to be hereinafter more fully set forth. In forming the agitator vanes or ribs 7, the said ribs or vanes may be pressed outwardly from the material forming the disk 6, and as shown to advantage in Figure 2 these vanes 7 are of elongated hollow construction.

The upper edge or surface 10 of the vanes at the forward end of the vanes merge into downwardly sloping surfaces or vertical edges 11 merging into the disk-like body 6 at the outer peripheral edge of the disk. At the opposite ends the surface 10 merges into a downwardly and inwardly inclined surface 12, which surface 12 gradually increases in width as it approaches the lower end of the shaft 9. The side walls 14 converge upwardly toward the upper edge or surface 10 as indicated to advantage in Figure 4.

This particular construction of each of the vanes 7 render the vanes thoroughly reliable, practical and efficient for agitating purposes especially in conjunction with wash tubs.

The upper agitator member is designated generally by the reference character B. The agitator member B comprises a circular body portion 15 which may be formed of wood or aluminum or any other suitable material, the body portion 15 has an annular beveled edge portion 16 merging into a flat bottom face 17 of lesser diameter than the body per se.

Projecting downwardly and outwardly from the beveled or sloping surface 16 at the periphery of the body or agitating pegs 18 there being preferably four of such agitating pegs. The body 15 is provided with a centrally located opening 19 to accommodate the upper end portion of the shaft 5 whereby the upper agitator member B may be slidable on said shaft. The body 15 at the opening 19 thereof is further provided with diametrically opposed notches or keyways 20 for cooperation with the key members or ribs 9 of said shaft 5.

Conforming to the opening 19 and key-

ways 20 is a plate 21, which plate 21 constitutes a reinforcing place and is bolted or otherwise secured to the upper face of the body 15 as at 22.

5 Manifestly, in operation, the upper agitator member is keyed to the upper end portion of the shaft 5 of the lower agitator member, and this shaft 5 is then in turn keyed to the drive shaft of a washing machine not 10 shown for rotation therewith, the vanes 7 agitating and thoroughly shifting the clothes or articles and the bottom or lower portion of the washing machine and the agitating pegs 18 of the upper agitator member B per- 15 forming a like operation on the articles or clothes which may have risen toward the top of the washing machine.

From the foregoing then it will be seen that I have devised a thoroughly practical 20 and reliable agitator for washing machines which will thoroughly agitate and shift the clothes at the top and bottom of the machine, and which agitator may be readily and easily applied to a conventional type of washing 25 machine without necessitating material alterations in the structure of the washing machine.

It will be also appreciated that a double agitator of this character will be found capable of doing quicker and better work than the single agitator as is now in use.

Even though I have herein shown and described the preferred embodiment of my invention, it is to be understood that the same 35 is susceptible to changes fully comprehended by the spirit of the invention as herein described, and the scope of the appended claims.

Having thus described my invention, what I wish to claim as new is:

40 1. An agitator of the class described comprising a shaft, means at the upper end of said shaft to facilitate the keying of the shaft to the drive shaft of a washing machine, a disk formed integrally on said first mentioned shaft at the lower end of said first mentioned shaft, agitator ribs formed integrally on said disk and radiating from the adjacent end portion of said first named shaft, said rib having upwardly and rearwardly inclined forward edges merging into substantially flat straight upper edges, which upper edges in turn merge into downwardly and rearwardly inclined edges, the latter edges merging at their lower end into the 50 lowermost edge of said shaft, a second disk slidable on said first mentioned shaft, means for keying said second disk to said first mentioned shaft, and a plurality of circumferentially spaced downwardly and outwardly 55 extending pegs carried by the last mentioned disk.

60 2. An agitator of the class described comprising a shaft, longitudinally extending cleats integral with the shaft on diametri- 65 cally opposite sides thereof, means for keying

said shaft at its upper end to the drive shaft of the washing machine, a disc integral on the first mentioned shaft at the lower end thereof, radial agitator ribs integral on said disc and radiating from the adjacent ends of said shaft, said ribs intermediate their ends inclining downwardly from their upper edges to provide downwardly and rearwardly inclined inner edges merging at their lower ends into the lower end of said shaft, said ribs at their forward edges inclining upwardly and rearwardly from the peripheral edge of said disc, a second disc having a central aperture for slidably accommodating said shaft, said second disc at diametrically opposite sides of said aperture having vertical notches formed therein for reception of said cleats for preventing relative rotation of said second disc and shaft circumferentially spaced agitating pegs extending downwardly and outwardly from said second disc.

3. An agitator of the class described comprising a shaft, said shaft at one end being provided with means for keying said shaft to the drive shaft of a washing machine, and said first mentioned shaft at its opposite end having a disc formed integral therewith, ribs integral with said discs and said lower end of the first mentioned shaft, and radiating from said last mentioned shaft, said ribs intermediate their ends inclining downwardly from their upper edge to provide downwardly and rearwardly inclined edges merging at their lower ends into the first mentioned shaft, ribs inclining upwardly and rearwardly from the peripheral edge of said discs, and a movable disc slideable on said first mentioned shaft toward or away from the second mentioned shaft, said movable disc having the periphery thereof provided with 105 agitating pegs depending downwardly therefrom.

In testimony whereof I affix my signature.
HENRY KOLAR.
